[57] CLAIM

The ornamental design for a soccer ball radio, as shown and described.

DESCRIPTION

FIG. 1 is a perspective, top and front view of a soccer ball radio showing my new design;

FIG. 2 is a rear elevation view thereof;

FIG. 3 is a top plan view thereof;

FIG. 4 is a right side view thereof, the left side view being a mirror image; and,

FIG. 5 is a bottom view thereof.

The broken line showing of the headphone and wires on FIG. 1 is for illustrative purposes only and forms no part of the claimed design.

1 Claim, 3 Drawing SheetsFIG. 1

FIG. 2

FIG. 3

FIG. 4

FIG. 5

UNITED STATES PATENT AND TRADEMARK OFFICE
CERTIFICATE OF CORRECTION

PATENT : Des. 420,002
DATED : Feb. 1, 2000
INVENTOR(S) : Armando L. Arcos

It is certified that error appears in the above-identified patent and that said Letters Patent is hereby corrected as shown below:

Title Page, item [75],
Inventor: Armando L. Arcos
4921 Seminary Road #1505
Alexandria, VA 22311

Signed and Sealed this
Fifteenth Day of May, 2001
